DESIGN FOR A DISPLAY STAND

Michael A. Mauro and Francesco J. Galante,
New York, N. Y.

Application May 8, 1940, Serial No. 92,215

Term of patent 3½ years

To all whom it may concern:

Be it known that we, Michael A. Mauro and Francesco J. Galante, both citizens of the United States and both residents of New York city, both in the county of New York and State of New York, have invented a new, original, and ornamental Design for a Display Stand, of which the following is a specification, reference being had to the accompanying drawing, forming a part thereof.

Fig. 1 is a front elevational view of a display stand, showing our new design.

Fig. 2 is a rear perspective view of the same.

Fig. 3 is a side elevational view of the same.

The characteristic feature of our design resides in the combination of the disclosed barrel shaped board having horizontal rows of openings with the specific stand at the back of the board and the three ornamental projections on the front top area of the board.

We claim:

The ornamental design for a display stand, as shown and described.

MICHAEL A. MAURO.
FRANCESCO J. GALANTE.
